UNITED STATES PATENT OFFICE.

WILLIAM F. FOWLER AND EDWARD A. KING, OF CINCINNATI, OHIO,
ASSIGNORS OF ONE-THIRD TO CHARLES H. KRIPPENDORF, OF
CINCINNATI, OHIO.

METHOD OF LASTING SHOES.

SPECIFICATION forming part of Letters Patent No. 777,197, dated December 13, 1904.

Application filed January 18, 1904. Serial No. 189,460. (No model.)

To all whom it may concern:

Be it known that we, WILLIAM F. FOWLER and EDWARD A. KING, citizens of the United States, residing at Cincinnati, in the county of Hamilton and State of Ohio, have invented certain new and useful Improvements in Methods of Lasting Shoes, of which the following is a specification.

Our invention relates to an improvement in shoes and in the method of their construction, especially to those in which the vamps or tips are cut out of patent-leather or Russia calf or any other kind of firm leather. The vamps are generally enforced by a lining and a middle lining, usually of twill or drill. Great difficulty has heretofore been experienced in the lasting of the toe portion of shoes made from such leather. In lasting the toe portion of the shoe the leather, lining, middle lining, and the piece which forms the box have to be drawn, stretched, and gathered around the toe. As the linings and the piece which forms the box are always of different elasticity than the vamp or tip, it is necessary that the different parts be held compactly together, as there is apt to be creeping or puckering of the parts, causing the vamp or tip to wrinkle or crack in the lasting operation. In pulling the upper over the toe part of the last a very large percentage, especially of such vamps or tips which are cut out of patent-leather, will crack and either have to be ripped off and revamped, re-tipped, and relasted or patched up, and thus involve great expense and making an imperfect shoe.

The object of our invention is to overcome these difficulties.

By our method we obtain smooth uniform lasting of the toe and avoid the trouble, the imperfections, and expense above mentioned, thereby making a great saving in the cost, as well as materially adding to the appearance of the shoe.

The features of our invention are more fully set forth in the description of the accompanying drawings, forming a part of this specification, in which—

Figure 1 is a top plan view of the front portion of the vamp and tip finished for lasting.

Fig. 2 is a section on line *xx*, Fig. 1. Fig. 50
3 is a side elevation of the front portion of
vamp and tip after the lasting operation. Fig.
4 is an enlarged section on line *ww*, Fig. 3, in
which the welt is shown as attached to one
side.

55

The following is the method which we apply in lasting the shoe:

A represents the vamp or upper of the shoe.

B represents the tip.

C represents the middle lining, and *D* the 60
part which forms the box, which is usually
made of split leather or canvas.

The vamp, the tip, and the middle and the regular lining are fitted together in the usual manner. In the present method the tip, the 65
vamp, the middle lining, and the piece which forms the box are loose at the toe end. Our
method differs. We pass a line of stitches *a*
around the toe end through the tip, vamp,
middle lining, and the piece which forms the 70
box, so as to firmly hold these parts together
and prevent the stretching of one more than
the other in the operation of the lasting. This
line of stitches *a* is outside or below the seam
b, by means of which after the upper is lasted 75
the welt *d* or sole is sewed to the upper.

a represents the line of stitches connecting
the various parts (tip, vamp, middle lining,
and the piece which forms the box) together,
as shown in Figs. 1 and 2. *b* represents the 80
seam by which the welt *d* or sole is attached
to the upper. After these parts have been
fitted and lasted as herein described the shoe
is finished in the ordinary manner. By this
method of firmly securing the various parts 85
together at the end of the toe they are drawn
uniformly without danger of wrinkling, puck-
ering, or cracking, occasioned by the common
method of manufacture.

We have shown the construction of shoe 90
with the tip applied to the toe portion of the
vamp, as this form is the most difficult to last;
but the advantages herein described are ob-
tained also when the tip is omitted and the
toe portion of the vamp, middle lining, and 95
box-piece are employed and firmly secured to-
gether by the marginal line of stitches *a*.

E represents the insole, *e* the nails for tack-

ing the upper to the last, and *h* the wire for holding the toe portion to the last until the upper has been secured to the insole in the usual manner.

5 Having described our invention, we claim—

The method of lasting a shoe, which consists in connecting together the vamp, co-parts forming the upper by a marginal line of stitches, then drawing the same over the last and tacking the parts to the insole, then se-

curing the insole to the upper by fastening means inside of the said marginal line of stitches, substantially as described.

In testimony whereof we have hereunto set our hands.

WILLIAM F. FOWLER.
EDWARD A. KING.
